RAILWAY SIGNALING MECHANISM. *

1,401,511.

Specification of Letters Patent. Patented Dec. 27, 1921.

Application filed September 2, 1921. Serial No. 497,827.

To all whom it may concern:

Be it known that I, CHARLES R. BEALL, a citizen of the United States, residing at Swissvale, in the county of Allegheny and State of Pennsylvania, have invented certain new and useful Improvements in Railway Signaling Mechanism, of which the following is a specification.

My invention relates to railway signaling mechanisms, and particularly to mechanisms for the operation and control of signals of the semaphore type. In signals of this character, the semaphore is usually biased to the stop position by gravity and is moved to its other indicating position or positions by a motor, an electrically controlled holding device being provided to hold the semaphore in its operated position or positions and sometimes to clutch the semaphore to the motor.

When the holding device is of the tractive magnet type, it requires more current to move the armature to the closed position than to keep it in such position, and, consequently, it is desirable from the point of view of power consumption to reduce the current supplied to the holding magnet after the holding armature controlled thereby has been closed. One feature of my invention is the provision of a novel means for accomplishing this result.

I will describe two forms of signaling mechanisms embodying my invention, and will then point out the novel features thereof in claims.

In the accompanying drawings, Figure 1 is a view, partly diagrammatic and partly in elevation, showing one form of signal mechanism embodying my invention. Figure 2 is a view showing a modification of the mechanism shown in Fig. 1 and also embodying my invention.

Similar reference characters refer to similar parts in each of the views. Referring first to Fig. 1, the signal mechanism comprises a semaphore S biased to the horizontal or stop position, together with a motor M for moving the semaphore to an inclined or caution position in which it is 45° from the stop position, and to a vertical or proceed position in which the semaphore is 90° from the stop position. The motor M is operatively connected with the semaphore through the medium of suitable mech-

anism indicated diagrammatically by the dash lines 58 and 58^a, and which mechanism includes a ratchet wheel 10. Coöoperating with this ratchet wheel is a pawl 13, which, when held in engagement with the ratchet wheel, operates to hold the semaphore S in the caution or proceed position. The pawl 13 is biased to such position that it is out of engagement with the ratchet wheel 10, but is movable into engagement with this ratchet wheel by a holding magnet K comprising a motor coil 16 and a main coil 15, which magnet controls the pawl 13 through the medium of an armature 14. Operatively connected with the pawl 13 is a contact 47 which is closed when the pawl is out of engagement with the ratchet wheel and is opened when the pawl is moved into operative position.

The reference character C designates a circuit controller which is operated in accordance with the movements of the semaphore S and which, as here shown, is operatively connected with such semaphore through the medium of suitable mechanism indicated diagrammatically by dash lines 59. This circuit controller comprises two contact segments 43 and 44, and four pairs of contact fingers coöoperating therewith. The arcs of the circuit controller are so arranged that contact 20—20^a is closed from the 0 to 43 degree position of the semaphore; contact 37—37^a closes at the 40 degree position and opens at the 88 degree position, contact 29—29^a is closed from the 0 to 55 degree position of the semaphore, and contact 41—41^a closes at the 50 degree position and remains closed at the 90 degree position of the semaphore.

The motor M and the holding magnet K are supplied with energy by currents of different voltages, the source being here shown as batteries B and B^a. The supply of current from these batteries to the motor and holding magnet is governed by two relays H and D, which relays may be controlled in any suitable manner and by any suitable means, having nothing to do with my present invention.

The operation of the mechanism is as follows: When the relays H and D are both open, as shown in the drawing, the semaphore S is in the horizontal or stop position and the other parts of the apparatus

- are in the positions in which they are illustrated. When it is desired to move the semaphore S to the caution position, relay H is closed, whereupon current flows from the upper terminal of battery B, through wire 17, contact 18 of relay H, wires 33 and 19, contact 20—20^a, wires 21 and 22, armature 11 of motor M, field winding 12 of this motor, wire 23, motor coil 16 of magnet K, and wire 24 to the lower terminal of battery B. Current also flows from wire 21, through wire 46, contact 47, wire 48 and snubbing resistance 45 to wire 23, but the supply of current to motor coil 16 causes magnet K to attract the armature 14, thereby moving pawl 13 into its operative position and opening the contact 47, so that the snubbing resistance 45 is immediately cut out of the motor circuit. Motor M then operates to move the semaphore S toward the caution position. When the semaphore S reaches the 43° position, motor M becomes deenergized due to the opening of contact 20—20^a, but the movement of the semaphore S continues about two degrees, so that the semaphore comes to rest in the 45° or caution position. The closing of relay H also closes a circuit which passes from the lower terminal of battery B^a, through wire 25, contact 26 of relay H, wires 27 and 28, contact 29—29^a, wires 30 and 31, main coil 15 of holding magnet K, and wires 32 and 24 to the upper terminal of battery B^a. This circuit remains closed after the semaphore S reaches the caution position, so that the semaphore is held in this position due to the supply of current to winding 15 from the low voltage battery B^a.
- If now it is desired to move the semaphore S to the proceed position, relay D is closed, thereby closing a circuit which passes from the upper terminal of battery B, through wire 17, contact 18 of relay H, wires 33 and 34, contact 35 of relay D, wire 36, contact 37—37^a, which is then closed, wires 21 and 22, armature 11 and field winding 12 of motor M, wire 23, motor winding 16 and wire 24 to the lower terminal of battery B. Motor M then operates to move the semaphore S toward the proceed position. Contact 29—29^a opens at the 55° position of the semaphore, but contact 41—41^a has in the meantime become closed at the 50° position of the semaphore, so that the main coil 15 of magnet continues to be energized through a circuit which passes from the lower terminal of battery B^a, through wire 25, contact 26 of relay H, wires 27 and 38, contact 39 of relay D, wire 40, contact 41—41^a, wires 42 and 31, winding 15 of magnet K, and wires 32 and 24 to the upper terminal of battery B^a. Contact 37—37^a opens at the 88° position of the semaphore, thereby deenergizing motor M, but the drift of the semaphore is sufficient to carry it to the full pro-

ceed position, where it is held by the main coil 15 of magnet K because contact 41—41^a remains closed in this position.

If now it is desired to return the semaphore from the proceed position to the caution position, relay D is permitted to open but relay H is kept closed. The opening of relay D opens both the motor operating circuit and the holding circuit for magnet coil 15, so that the semaphore S returns toward the caution position. Owing to the fact that magnet K is entirely deenergized, contact 47 is now closed, thereby closing a circuit for motor M through the snubbing resistance 45. The motor M then acts as a generator and so serves as a dynamic brake to retard the movement of the semaphore S. When the 43° position of the semaphore is reached the motor M and magnet coil 16 become energized, due to the closing of contact 20—20^a, so that the motor M will return the semaphore to the 45° or caution position, at which point it will be held because of the fact that coil 15 of magnet K is now energized. In this connection it should be noted that the supply of current from battery B^a to coil 15 is not sufficient to move the pawl 13 to its operative or holding position, but is sufficient to hold this pawl in such position after it has been moved thereto by the supply of current to the motor coil 16.

When the semaphore S is to return to its stop position, relay H is permitted to open, thereby deenergizing magnet K and preventing energization of motor M, so that the semaphore as well as all other parts of the apparatus return to their initial positions wherein they are shown in the drawing.

Referring now to Fig. 2, the apparatus shown therein is the same as that shown in Fig. 1, except that the supply of current from batteries B and B^a is controlled by a polarized relay P, and the snubbing resistance 45 is governed by an additional circuit controller segment 49 which co-operates with contact fingers 50—50^a. The contact 50—50^a is arranged to be closed from the 35° to 45° position of the semaphore S but is open at all other times.

When the relay P is open, as shown in the drawing, all of the signal circuits are open, so that the semaphore S is in the stop position. When the semaphore is to be moved to the caution position relay P is energized in such direction that its polarized contacts 53 and 55 remain open, whereupon motor operating current flows from the upper terminal of battery B, through wire 17, neutral contact 52 of relay P, wires 33 and 19, contact 20—20^a, wires 21 and 22, armature 11 and field winding 12 of motor M, wire 23, motor coil 16 of magnet K, and wires 24 and 24^a to the lower terminal of

battery B. The energization of relay P in the direction specified also closes a holding circuit which passes from the lower terminal of battery B^a, through wire 25, upper point 5 of contact 54 of relay P, wires 27 and 28, contact 29—29^a, wire 31, main coil 15 of magnet K, and wires 32, 24 and 24^a to the upper terminal of battery B^a. Semaphore S then moves to the caution position where 10 it stops owing to the deenergization of motor M by the opening of contact 20—20^a. To continue the movement of the semaphore S to the proceed position, relay P is energized in such direction as to cause its polar 15 contacts 53 and 55 to close, whereupon a new operating circuit is closed, which passes from the upper terminal of battery B^a, through wire 17, contact 52 of relay P, wires 33 and 34, contact 53 of relay P, wire 36, contact 37—37^a, wires 21 and 22, armature 20 11 and field winding 12 of motor M, wire 23, coil 16 of magnet K, and wires 24 and 24^a to battery B. A new holding circuit is also closed, passing from the lower terminal 25 of battery B^a through wire 25, upper point of contact 54, wires 27 and 38, contact 55, wire 40, contact 41—41^a, wires 42 and 31, magnet coil 15 and wires 32, 24 and 24^a to battery B^a. Semaphore S is then moved 30 to the proceed position at which point the motor M is deenergized due to the opening of contact 37—37^a.

When the semaphore S is to return from the proceed to the caution position the energization of relay P is reversed, thereby opening the last-traced holding circuit at contact 35 55 of relay P. When the semaphore reaches the 45° position the snubbing resistance 45 is shunted by the snubbing contact 50—50^a, so that motor M is placed on short circuit 40 through this contact, and so the tendency of this motor to retard the movement of the semaphore at this point by generator action is stronger than with the arrangement shown 45 in Fig. 1. This excessive retardation overcomes the tendency of the semaphore to drift below the 43° position at which point current is supplied to the motor through contact 20—20^a, and such current then returns 50 the semaphore to the 45° position where it is held by current furnished to magnet coil 15 through the 45° holding contact 29—29^a.

In Fig. 2 it will be noted that the contact 55 54 of the polarized relay P is provided with a back point. The function of this is to place the main coil 15 of holding magnet K on short circuit during reversal of relay P while semaphore S is in the caution position. The short circuit path through coil 15 at 60 such time will be apparent from the drawing, and as is well understood, it serves to increase the retardation of the holding magnet, which, must be slow-releasing in character in order to avoid release of the semaphore during reversal of relay P.

It will be observed that in both of the illustrated forms of my invention the power for operating the semaphore is supplied by a battery B, while the power for holding the semaphore in the caution and proceed positions is supplied by a separate battery B^a. The use of this separate holding battery has several advantages. It permits the use of a lower voltage on the holding magnet for holding the semaphore in its operated positions, and this lower voltage makes it possible to wind the coil 15 with wire of comparatively large cross-section, thus reducing the cost of this coil and also reducing the susceptibility of the coil to damage by lightning discharge. Furthermore, since the coil is of large wire and has a comparatively few number of turns, the liability of having magnet trouble due to sneak currents over high resistance grounds or crosses is minimized. 70 75 80 85

The use of a separate battery for holding purposes allows a comparatively uniform discharge from all cells of the battery and insures a comparatively uniform voltage on coil 15 of the holding magnet throughout the life of the battery. When the same battery is used for operating the semaphore and for supplying power to the holding magnet, the voltage on the holding magnet is very 90 95 materially reduced during operation of the semaphore because of the reduction in the voltage at the terminals of the battery due to the comparatively heavy current taken by the motor. 100

On account of the fact that the discharge from the low voltage battery B^a is comparatively small and is of a constant value, it is possible in the practice of my invention to use the battery to a point nearer complete 105 exhaustion than is possible when a single battery is used for operation and holding. This is due to the fact that the current required for the motor constitutes a rather severe load upon the battery, and therefore 110 renewals must be made before the battery is entirely exhausted if interruptions to service are to be avoided.

Although I have herein shown and described only two forms of signal mechanisms embodying my invention, it is understood that various changes and modifications may be made therein within the scope of the appended claims without departing from the spirit and scope of my invention. 115

Having thus described my invention, what I claim is:

1. Railway signaling mechanism comprising a semaphore, a motor for operating said semaphore, a holding magnet having a motor coil and a main coil, two sources of current of different voltages, and means including circuit controllers operated in accordance with the movements of said semaphore for simultaneously establishing a circuit in 120 125 130

cluding the high-voltage source and said motor and said motor coil, and a circuit including the low-voltage source and said main holding coil, and for subsequently interrupting the first of said circuits.

2. Railway signaling mechanism comprising a semaphore, a motor for operating said semaphore, a holding magnet having a motor coil and a main coil, two sources of current of different voltages, and means including circuit controllers operated in accordance with the movements of said semaphore for energizing said motor and said motor coil from the high-voltage source and said main coil from the low-voltage source while the motor is moving the semaphore, and for deenergizing said motor and said motor coil when the semaphore reaches substantially its operated position.

3. Railway signaling mechanism comprising a semaphore, a motor for operating said semaphore, a holding magnet having a motor coil and a main coil, two sources of current of different voltages, and means including circuit controllers operated in accordance with the movements of said semaphore for energizing said motor and said motor coil from the high-voltage source while the motor is operating the semaphore, and for energizing said main coil from the low-voltage source before the motor is deenergized and after the operation of the semaphore by the motor ceases.

4. Railway signaling mechanism comprising a semaphore, a motor for operating said semaphore, a holding magnet having a motor coil and a main coil, two sources of current of different voltages, means for energizing said motor and said motor coil from the high-voltage source while the motor is operating the semaphore and for deenergizing said parts just before the semaphore reaches the operated position, and means for energizing said main coil from said low-voltage source before the motor is deenergized and for continuing the energization of the main coil after the semaphore reaches the operated position.

5. Railway signaling mechanism comprising a semaphore, a motor for operating said semaphore, a holding magnet having a motor coil and a main coil, two sources of current of different voltages, an operating circuit including said motor, motor coil and high-

voltage source, a holding circuit including 55 said main holding magnet coil and the low-voltage source, means for closing said operating circuit when the motor is to drive the semaphore and for opening said circuit before the semaphore reaches the operated 60 position, and means for closing said holding circuit before the operating circuit is opened and for keeping the holding circuit closed until after the semaphore reaches its operated position.

6. Railway signaling mechanism comprising a semaphore, a motor for operating said semaphore, a holding magnet having a motor coil and a main coil, two sources of current of different voltages, two circuit controllers operated in accordance with movements of 70 said semaphore, the first controller being closed during movement of the semaphore to nearly its operated position, and the second controller being closed before the first 75 opens and remaining closed in the operated position of the semaphore; a circuit including the high-voltage source, the motor, the motor coil and the first circuit controller; and a second circuit including the low-volt- 80 age source, the main coil of said holding magnet and the second circuit controller.

7. Railway signaling mechanism comprising a semaphore biased to stop position, a motor for moving it to caution and proceed 85 positions, a holding magnet having a motor coil and a main coil, two sources of current of different voltages, means for energizing said motor and said motor coil from the high-voltage source while the motor is operating 90 the semaphore to the caution position and for deenergizing said parts just before the caution position is reached, means for energizing said main coil from the low-volt- 95 age source before the motor circuit is opened and after the semaphore reaches the caution 100 position, means for again energizing the motor and the motor coil from the high-voltage source while the motor is operating the semaphore from caution position to proceed position and for deenergizing said parts just before proceed position is reached, and means for again energizing said main coil from the low-voltage source before the motor circuit is opened and after the semaphore 105 reaches the proceed position.

In testimony whereof I affix my signature.
CHARLES R. BEALL.
